CLAIM

The ornamental design of a golf bag mug, as shown and described.

DESCRIPTION

FIG. 1 is a front elevation of a golf bag mug showing our new design, the cover being in place and the rear elevation being a mirror image thereof;

FIG. 2 is a right side elevation thereof;

FIG. 3 is a left side elevation thereof;

FIG. 4 is a top plan thereof;

FIG. 5 is a bottom plan thereof;

FIG. 6 is a front elevation of the golf bag mug without the cover, the rear elevation being a mirror image thereof;

FIG. 7 is a right side elevation thereof;

FIG. 8 is a left side elevation thereof; and,

FIG. 9 is a top plan, the bottom plan being identical to FIG. 5.

FIG. 1

FIG. 2

FIG. 3

FIG. 4

FIG. 5

FIG. 6

FIG. 7

FIG. 8

FIG. 9
